UNITED STATES PATENT OFFICE.

ALVIN S. STRICKLER AND WILLIAM H. STRICKLER, OF KEOKUK, IOWA.

CARPET-RACK.

SPECIFICATION forming part of Letters Patent No. 693,458, dated February 18, 1902.

Application filed September 13, 1899. Serial No. 730,323. (No model.)

To all whom it may concern:

Be it known that we, ALVIN S. STRICKLER and WILLIAM H. STRICKLER, citizens of the United States, residing at Keokuk, in the county of Lee and State of Iowa, have invented certain new and useful Improvements in Carpet-Racks, of which the following is a specification.

Our present invention pertains to improvements in display stands or cabinets for carpets and the like, the construction being illustrated in the accompanying drawings, wherein—

Figure 1 is a front plan view of the apparatus; Fig. 2, an end elevation partly broken away; Fig. 3, a perspective view of one of the spindles or supports; Fig. 4, a sectional view showing the spindle in its relation to a roll of carpet and the frame of the cabinet, and Fig. 5 a transverse sectional view of a roll of carpet and the spindle therein.

The object of our invention is to provide a display stand or cabinet for holding rolls of carpet or the like wherein the carpet may be brought to the view of the purchaser and rewound upon the roll without any difficulty.

The invention has for its further object the construction of a spindle or support which when inserted into the core of the roll will embrace and clamp the edge of the carpet, portions of the spindle at the same time interlocking.

Referring to the drawings, A, B, and C indicate three uprights of the framework, connected at the top by a cross member D and at the bottom by a cross member E, the lower ends of the uprights A, B, and C being provided with suitable feet or supports F. The rolls of carpet or the like are designed to be held between the uprights, as best shown in Fig. 1. To hold them in such position, we employ a spindle or support which in the form illustrated comprises two separate members of like shape adapted to pass through the core of the roll and to interlock with each other, at the same time clamping the inner end of the carpet between them. Said spindle or support is best shown in Figs. 3 to 5, inclusive.

Each member of the spindle or support comprises a bar made straight or slightly taper-

ing from one end to the other and provided with an outwardly-extending flange or rib G upon one side thereof. At the smaller end of each section are formed two arms or fingers H-H or equivalent slot, groove, or opening, while near the larger end and extending out from the flat face thereof is a hook or projection I, the main body of which lies parallel with the flat face of the section. At the larger end of the section we provide a guard J, from which extends a stud-axle K. When the two sections which go to form the spindle are assembled, one is passed in at each end of the roll, and the inner end of the carpet lies between the flat faces which are adjacent to each other. As the sections are pushed into place the ribs G and the edges of the body proper bind against the carpet and form a close connection therewith, the hooks or projections I passing between the fingers H and overlapping the body of the opposite section, as is clearly indicated in Fig. 4, thus locking the two members together. As indicated, the form of the interlocking portions is a matter of secondary consequence, the essential point being that the end of each section be arranged to engage or interlock in some manner with the companion section or member. Before the sections or members are passed into the roll, however, we pass over one of them a power-wheel L. (Best shown in Fig. 3.) As will be noted, said wheel is provided with a central opening of such form that it will pass over the member and up next to the guard J. The formation of the arms of the wheel is such that the face which comes next to the end of the roll will lie flat against said roll, while the outer faces project slightly in order that the operator may secure a firm and easy grasp thereon.

Secured to the inner faces of the uprights of the frame are suitable supports or bearings M, adapted and designed to receive and hold the stud-axles of the spindle. These bearings are provided with a rounded seat N and with two upwardly and outwardly inclined faces O, which serve to assist in guiding the stud-axles to their seats.

To provide a suitable support for the carpet as it is withdrawn from the rolls, we employ a guard-bar P, which comprises a series

of sections of a length sufficient to pass from one upright to the next. In said uprights we secure arms or pins Q, provided at their outer ends with seats or sockets adapted to receive 5 the ends of the bars and hold them in place. To guide the carpet and keep it straight as it is drawn off or wound upon the rolls, suitable guide-pins R are employed, which in the form illustrated are nothing more or less than ordinary screw-eyes. Any one of these bars may be removed when it is desired to take out a roll of carpet or put a new one in place. As will be noted upon reference to Fig. 2, 10 the bars serve to keep the carpet as it is withdrawn from the roll from rubbing upon the roll 15 next below.

It will be seen that by simply turning the hand-wheel L any carpet which has been withdrawn from a roll may be readily rewound 20 thereon.

The whole apparatus may be taken down and stored in a small compass and may be readily assembled by one possessing but little mechanical skill.

25 Having thus described our invention, what we claim is—

1. A spindle or support for a roll of carpet or the like, comprising two members of like form; and means carried by said members for 30 causing them to interlock as they are brought to position and to leave a space intermediate their opposing faces for the reception of the inner end of the carpet-roll, whereby the inner end of the carpet may be clamped between 35 them, substantially as described.

2. A spindle or support for a roll of carpet or the like, comprising two members of like form; means carried by said members for causing them to interlock as they are brought 40 to position and to leave a space intermediate their opposing faces for the reception of the inner end of the carpet-roll, whereby the inner end of the carpet may be clamped between them; guards formed upon the outer 45 ends of said members; and stud-axles extending out from said guards.

3. A spindle or support for a roll of carpet or the like, comprising two members of like form, each member having fingers or arms H 50 formed at one end; hooks I adapted to pass between the arms or fingers H and to overlap the body of the opposite member; and

stud-axles K extending out from the ends of the members.

4. A spindle or support for a roll of carpet 55 or the like, comprising two members of like form, each member having a flat face, a rib G extending longitudinally of the member, arms H formed at one end of the member, and a hook I extending out from the flat face 60 near the outer end of the member; a guard J; and a stud-axle extending out from the said guard.

5. A spindle or support for a roll of carpet or the like, comprising two members of like 65 form adapted to interlock as they are passed in from opposite ends of a roll of carpet, and to embrace or clamp the inner end of the carpet; and a hand-wheel mounted upon the spindle. 70

6. A spindle or support for a roll of carpet or the like, comprising two members; and means for interlocking said members with a space left intermediate their opposing faces, whereby the inner end of the carpet may be 75 clamped between them as the parts are brought to position, substantially as described.

7. In a cabinet or rack for displaying carpets and the like, the combination of an open 80 frame or support, provided with a series of openings in its front face; means for holding a roll of carpet exposed to view within the frame; independent pins or arms fitting within the openings of said frame; and a guard-bar carried by said arms. 85

8. In a cabinet or rack for displaying carpets and the like, the combination of an open 90 frame or support provided with a series of openings in its front face; means for holding a roll of carpet exposed to view in said frame; independent pins Q fitting within said openings, said pins being provided with sockets in their outer ends; and a removable guard-bar carried by said arms. 95

In testimony whereof we have signed our names to this specification in the presence of two subscribing witnesses.

ALVIN S. STRICKLER.
WILLIAM H. STRICKLER.
